UNITED STATES PATENT OFFICE

130,079

DESIGN FOR A PORTABLE SERVICE TABLE

Gladys W. Weller, New York, N. Y.

Application April 7, 1941, Serial No. 100,204

Term of patent 7 years

To all whom it may concern:

Be it known that I, Gladys W. Weller, a citizen of the United States, residing at New York, in the county and State of New York, have invented a new, original, and ornamental Design for a Portable Service Table, of which the following is a specification, reference being had to the accompanying drawing, forming part thereof.

Figure 1 is a perspective view showing my new design of the portable service table in folded condition;

Figure 2 is a like view of the portable service

table in expanded condition and with drawers and tray partially open; and

Figure 3 is a perspective view of the portable service table seen from the diagonally opposite corner from Figures 1 and 2 with the drop leaf and handle extended and with the drawers and tray in closed position.

I claim:

The ornamental design for a portable service table, as shown and described.

GLADYS W. WELLER.
